(57) **CLAIM**

The ornamental design for a gasoline pump handle clip, a
shown and described.

DESCRIPTION

FIG. 1 is a perspective view of a gasoline pump handle clip
showing my new design.

FIG. 2 is a top view of the gasoline pump handle clip as
shown in FIG. 1 showing my new design.

FIG. 3 is a bottom view of the gasoline pump handle clip as
shown in FIG. 1 showing my new design.

FIG. 4 is a front view of the gasoline pump handle clip as
shown in FIG. 1 showing my new design.

FIG. 5 is a back view of the gasoline pump handle clip as
shown in FIG. 1 showing my new design.

FIG. 6 is a right side view of the gasoline pump handle clip
as shown in FIG. 1 showing my new design; and,

FIG. 7 is a left side view of the gasoline pump handle clip
as shown in FIG. 1 showing my new design.
